METHOD FOR CURLING HAIR

Clara J. Altman, Detroit, Mich.

Application September 6, 1945, Serial No. 614,711

1 Claim. (Cl. 132—33)

This application relates to the art of curling hair.

A novel method for curling hair will now be described, with reference to the appended drawing whose Fig. 1 is a front view and whose Fig. 2 is a side view of a curler, in the form of a flat disc 11 of any suitable material, such as resilient rubber, about two inches in diameter, and having a central hole 12 which may be circular, as shown, or elongated, if desired. A radial slit 13 connects the hole to the edge.

For curling, the operator puts an end of a lock or multiple filament strand of hair through the center hole, from back to front of the disc, either by threading it through or by passing it through the slit, and then rolls the disc up towards the roots of the strand, by flopping the disc over and over and repeatedly opening up the slit to clear the lock, or strand, until the scalp is reached. The lock or strand will be curled around that portion 14 of the curler opposite the slit. Finally, the slit is permitted to close, so that the two wings 15 of the curler lock behind the strand curled around portion 14 and then the disc is given a 90° turn on its center, in a plane parallel to the scalp, so that the slit is positioned 90° relative from the position it occupied during the rolling step, to prevent accidental separation of the disc from the curl.

The curler hereof produces a curl of large diameter, considered more desirable than small diameter curls. In addition, the curler hereof will not break the hair, as contrasted with other types of curlers now known.

A person wearing as many as necessary of the 35 curlers here disclosed can be comfortable enough

so that the curlers do not interfere with sleeping. The discs will shift and yield slightly with respect to the scalp sufficiently to accommodate themselves to the movements of the person during sleeping.

A person wearing as many as necessary of the curlers here disclosed can still wear a bathing cap without danger of the cap being punctured by sharp edges or points. The curlers hereof, even when a large number of them are being worn, present no sharp edges or points to puncture a bathing cap.

Now having described the curler and the curling method herein disclosed, reference should be had to the claim which follows.

I claim:

A method for curling hair strands, employing a resilient disc about two inches in diameter, and formed with a central aperture about one half inch in diameter, and having a slit connecting the aperture to the edge of the disc, comprising (a) thrusting a multiple filament strand of hair through the disc from back to front thereof, (b) rolling the disc up towards the roots of the strand by flopping the disc over and over and repeatedly opening up the slit to clear the strand until the scalp is reached and finally permitting the slit to close so that the two wings of the curler lock behind the strand, and (c) turning the disc 90° on its center, in a plane parallel to the scalp, so that the slit is positioned 90° relative to the position it occupied during the rolling step, to prevent accidental separation of the disc from the curl.

CLARA J. ALTMAN.
